W. J. SHACKELTON,
INSULATION FOR ELECTRICAL APPARATUS,
APPLICATION FILED AUG. 16, 1917.

1,303,511.

Patented May 13, 1919.

Inventor:
William J. Shackelton
by *J.G. Roberts* Att'y.

UNITED STATES PATENT OFFICE.

WILLIAM J. SHACKELTON, OF SCOTCH PLAINS, NEW JERSEY, ASSIGNOR TO WESTERN ELECTRIC COMPANY, INCORPORATED, OF NEW YORK, N. Y., A CORPORATION OF NEW YORK.

INSULATION FOR ELECTRICAL APPARATUS.

1,303,511.

Specification of Letters Patent.

Patented May 13, 1919.

Application filed August 16, 1917. Serial No. 186,539.

To all whom it may concern:

Be it known that I, WILLIAM J. SHACKELTON, a citizen of the United States, residing at Scotch Plains, in the county of Union and State of New Jersey, have invented certain new and useful Improvements in Insulation for Electrical Apparatus, of which the following is a full, clear, concise, and exact description.

This invention relates to insulation for electrical apparatus and to a method for manufacturing the same, and more particularly to insulation adapted for use in transformers, repeating coils, loading coils and similar apparatus.

The general object of the invention is to provide a new and improved form of insulation having uniformly high dielectric strength and yet occupying a comparatively small amount of space.

The insulation heretofore used for the purpose above mentioned has usually consisted either of comparatively inflexible solid material, such as fiber or hard rubber tubes; or of flexible material of high dielectric strength, such as varnished muslin tape applied in layers between the parts to be insulated; or of material having inherently low dielectric strength impregnated with an insulating compound which is comparatively rigid under service conditions, such as cotton fabric impregnated with rosin. Each of these insulators ordinarily requires a comparatively large amount of space in order to provide high dielectric strength and is, therefore, not entirely satisfactory for all purposes. This element of space is exceedingly important in certain classes of apparatus, such as telephone transformers and repeating coils where the leakage inductances of the windings are predominating causes of low efficiency.

The preferred embodiment of this invention is illustrated in the drawing, wherein is shown a ring-shaped repeating coil having two windings insulated from one another by insulation made in accordance with the present invention, the coil being partially cut away to more clearly show the construction. While a ring-shaped coil having two windings is shown in the drawing, it will be clear that this invention is applicable to solenoidal or other shaped coils and to coils

having any number of superimposed windings.

Referring to the drawing, the core of the repeating coil is shown at 5 as composed of any suitable magnetic material, such as insulated iron wire wound in the form of a ring.

The core 5 is wrapped with a layer of any suitable insulating material, such as cotton tape 6; and upon this tape the inner winding 7 of insulated copper wire is wound in any well-known manner. The partially completed coil is then impregnated with a suitable insulating compound. The next step in the process of manufacture is the applying of a layer of insulating material of high dielectric strength which shall serve to separate the inner winding 7 and the outer winding hereinafter mentioned. The present invention resides in this insulating layer and the method of applying it now to be described.

The partially completed coil is preferably wound with a layer of impervious or partially impervious material 8, such as overlapping varnished muslin tape. Upon this is then wound a uniform thickness of insulating filler which may be in the form of a cotton tape 9. The coil is then preferably immersed in a heated molten insulating compound of high dielectric strength which may comprise a normally plastic or highly viscous mixture of rosin and rosin oil. The compound with the coil therein is then allowed to cool to its normally plastic or highly viscous semi-solid state. It is then reheated sufficiently to melt off the excessive amount of insulating compound which would otherwise adhere to the tape 9, and the coil is withdrawn from the compound covered with a uniform thickness of the insulating compound which is intimately intermingled with the cotton fabric.

The coil is then wound with a layer of impervious or partially impervious material such as overlapping varnished muslin tape 10. The tape 9, impregnated with and covered by the insulating compound of high dielectric strength, is thus held between the impervious or partially impervious layers of varnished muslin tape 8 and 10, and cannot be disturbed by future treatment of the repeating coil either in subsequent steps of manu-

facture or in any uses to which it may be put; the impervious inclosing layers 8 and 10 confine the plastic or viscous insulating compound to its predetermined location between the windings and prevent it from escaping by diffusing into the adjacent windings. The outer winding 11 of insulated copper wire is then wound on, and is covered by any suitable insulating material, such as overlapping cotton tape 12. The coil may then be impregnated with a suitable insulating compound in any well-known manner. When so constructed, a repeating coil is provided in which the windings are separated by insulating material of high dielectric strength occupying comparatively small space.

In actual commercial coils, it has been found that, with the same thickness of insulating material between the two windings of a coil, that which was applied in accordance with this invention broke down at approximately one and two thirds times the voltage which broke down that applied by the ordinary heretofore known methods.

Modifications of the exact structure and process hereinbefore described may obviously be made without departing from the scope of this invention as set forth in the accompanying claims; and it is to be understood that wherever the word "transformer" is used alone in the specification and claims, it is intended to include repeating coils, loading coils and other electrical apparatus wherein different parts are insulated from one another.

What is claimed is:

1. In a transformer, a layer of diffusive insulating compound, and a plurality of layers of material impervious to said compound forming a compartment inclosing said layer of insulating compound.
2. In a transformer, a plurality of windings, insulating means between said windings comprising a layer of diffusive insulating compound, and a plurality of layers of material impervious to said compound forming a compartment inclosing said layer of insulating compound.
3. In a transformer, a layer of plastic or highly viscous insulating compound, and a plurality of layers of material substantially impervious to said compound, said layer of insulating compound being retained between the layers of impervious material.
4. A transformer as specified in claim 3 in combination with an insulating filler intimately associated with said plastic or highly viscous insulating compound.
5. In a transformer, a plurality of wind-

ings, a plurality of layers of varnished muslin tape therebetween, and a layer of insulating compound comprising rosin and rosin oil between said layers of varnished muslin.

6. A transformer as specified in claim 5 in combination with a layer of cotton fabric intimately associated with said layer of insulating compound.

7. In a transformer, a plurality of windings, a plurality of layers of varnished muslin tape therebetween, and a layer of insulating compound between said layers of varnished muslin, said insulating compound comprising a highly viscous mixture of rosin and rosin oil.

8. A transformer as specified in claim 7 in combination with a layer of cotton fabric intimately associated with said layer of insulating compound.

9. The method of insulating superimposed windings which consists in applying a layer of impervious or partially impervious material over one of said windings, surrounding such layer with a suitable layer of plastic or highly viscous material of high dielectric strength, applying a second layer of impervious or partially impervious material over said plastic material, and superimposing a second winding thereover.

10. The method of insulating superimposed windings which consists in applying a layer of varnished muslin tape over one of said windings, immersing such partially completed coil in a molten insulating compound of high dielectric strength, allowing the compound to cool, reheating it sufficiently to allow the removal of said partially completed coil therefrom, applying a second layer of varnished muslin tape, and superimposing a second winding thereover.

11. The method of insulating a repeating coil having a plurality of superimposed windings, which consists in applying a layer of varnished muslin over one of said windings, applying a layer of cotton fabric thereover, immersing such partially completed coil in a molten compound comprising a normally highly viscous mixture of rosin and rosin oil, allowing said molten compound to cool before removing said partially completed coil therefrom, reheating said compound sufficiently to allow the removal of said coil therefrom, applying a second layer of varnished muslin thereover, and superimposing a second winding thereupon.

In witness whereof, I hereunto subscribe my name this 14th day of August, A. D. 1917.

WILLIAM J. SHACKELTON.
